UNITED STATES PATENT OFFICE.

MASON B. GIBERSON, OF DETROIT, MICHIGAN, ASSIGNOR TO THOMAS H. SIMPSON, OF DETROIT, MICHIGAN.

CAR-COUPING.

1,151,780.

Specification of Letters Patent. Patented Aug. 31, 1915.

Application filed December 10, 1912. Serial No. 735,925.

To all whom it may concern:

Be it known that I, MASON B. GIBERSON, a citizen of the United States of America, residing at Detroit, in the county of Wayne 5 and State of Michigan, have invented certain new and useful Improvements in Car-Couplings, of which the following is a specification, reference being had therein to the accompanying drawings.

10 The invention relates to car couplers of the Janney type, and has particular reference, first, to the means employed for locking and unlocking the knuckle; further in the means for opening the knuckle when 15 unlocked; and further in various features of construction as hereinafter set forth.

In the drawings: Figure 1 is an elevation of the coupler; Fig. 2 is a side elevation thereof, showing the lock-releasing device as 20 actuated from either the top or bottom; Fig. 3 is a similar view showing the releasing device at the bottom; Fig. 4 is a horizontal section; and Fig. 5 is a section similar to Fig. 2, where the top-releasing device is removed.

25 Car couplers of the Janney type are provided with swinging knuckles or coupling hooks of a substantially bell-crank lever form, the hooks being locked in closed position by a pin or other locking detent extending into the path of movement of the inner or shank arm of the knuckle. These locking pins are usually actuated from the top of the knuckle, which necessitates the 30 cutting away of the coupler body to form the entrance aperture, and consequently weakening the structure. With my improved construction, I employ a novel form of locking detent which may be introduced 35 into the body of the coupler in operative relation to the knuckle without materially cutting away or weakening the body structure. Furthermore, the construction is such that the detent may be released either from 40 the bottom or the top, preferably from the former.

In detail, A is the body of the coupler; B the hook or knuckle having the rearwardly-extending shank C, which is normally located in a recess in the body; and 45 D is a detent slidably engaging a vertically-extending recess E in the coupler body and extending into the path of the arm C so as to prevent the turning thereof.

In the handling of railway cars it is frequently necessary to unlock the couplers without opening the hooks, as for instance in shunting cars. I have therefore provided a retaining ledge or shoulder F in the recess E, which, when the detent is raised, will support the same and prevent reengagement when the operating lever is released. To raise the detent into engagement with this shoulder it may be actuated either from the top or from the bottom, and to this end is of the following construction: G is a downwardly-extending shank, preferably integral with the detent D and suitably cut away to clear the arm C of the knuckle. H is a shank preferably formed of a separate member and having a threaded lower end engaging a correspondingly threaded socket in the detent. The shank H is provided with a head I having an apertured ear J for coupling with a top 75 operating-lever, not shown, where such an actuating device is used. The downwardly-extending shank G is operated by a bell-crank lever K, which is fulcrumed at L at one side of the body and has a vertically-extending operating arm K', which is actuated with a straight rod, or other actuating connection, not shown.

With the construction as thus far described in operation, the detent D may be 85 lifted by either the bottom or top actuating device. When the lever K is actuated, it will bear against the lower end of the shank G, forcing the same upward and carrying the detent to a point above the path of the 90 arm C. Inasmuch, however, as it is necessary to retain the detent in this position by engaging it with the ledge F, I have provided the lever K with a cammed end portion M, which, after lifting the shank G, 95 will force the same laterally, engaging the detent with the shoulder F. A similar lateral movement is effected when the detent is actuated by the upwardly-extending shank H, by the angular movement of the 100 bell-crank lever or other actuating connection. Where it is desired to use only the bottom actuating device for the detent, the shank H may be disengaged from the member D, and the opening in the coupler, 105 through which said shank passes, may be stopped by a plug N.

To completely open the knuckle into posi-

tion for coupling, a lever O is arranged within the body of the coupler, having one arm P extending over the top of the detent. Sufficient clearance is provided to permit of movement of the detent into engagement with the ledge F without actuating the arm O of the lever, but a further upward movement will press the detent against said arm and swing the lever. The opposite arm Q 10 of the lever is so fashioned as to bear upon the swinging arm C of the knuckle, and the arrangement is such that the point of bearing on said arm Q is initially near the fulcrum of the lever O and upon a bearing on 15 the arm C at a distance from the fulcrum, thereby giving a powerful leverage. As the lever O swings, the contact-point travels outward upon the arm Q and inward upon the arm C, so as to give a progressively increasing speed with diminishing power. This arrangement lessens the work necessary in opening the knuckle, as the greatest force 20 is required to start the movement and comparatively little force is required to complete the same.

My construction is one which can be applied to any standard coupler of the Janney type without material change of construction, and the slight changes can be made at 30 small expense.

What I claim as my invention is:

1. In a car coupler, the combination with a locking detent having a downwardly extending shank, of a lever for engaging said shank to raise said detent, a shoulder for holding the detent in lock set position, and a cam engagement between said lever and shank for forcing the detent laterally of the plane of movement of the lever into engagement with said shoulder. 35

2. In a car coupler, the combination with a horizontally swinging knuckle and tail or locking arm therefor, of a vertically swinging lever for opening the knuckle, said lever having an arm extending obliquely to its pivotal axis and contacting with the tail of said knuckle, the initial point of contact being adjacent to the pivot of the lever and removed from the pivot of the knuckle, said point of contact traveling, during the opening of the knuckle, toward the pivot thereof and away from the pivot of the lever, the lever being held fixed from tilting movement transversely of its pivotal axis. 40

In testimony whereof I affix my signature in presence of two witnesses.

MASON B. GIBERSON.
